UNITED STATES PATENT OFFICE.

VINCENT A. MENUEZ, OF MEMPHIS, TENNESSEE.

DROP EXTENSION.

SPECIFICATION forming part of Letters Patent No. 761,844, dated June 7, 1904.

Application filed July 28, 1902. Serial No. 117,297. (No model.)

To all whom it may concern:

Be it known that I, VINCENT A. MENUEZ, a citizen of the United States, residing at Memphis, Shelby county, State of Tennessee, have 5 invented certain new and useful Improvements in Drop Extensions, of which the following is a specification.

My invention relates to certain new and useful improvements in drop extensions for 10 vapor-lamp chandeliers, and has especial reference to a support for vapor-lamps in which the reservoir for the gasoline or like liquid is placed at the proper height above the burners in order to give by gravity a sufficient pressure for the lights. It can also be used with 15 pressure-reservoirs, if so desired.

The object of my invention is to provide first a drop extension which is compact, simple, and positive in action and one which will take 20 up a minimum of space, so that it may be used on gasoline-lamps in rooms having low as well as high ceilings without adding a separate extension above the reservoir.

A further object of my invention is to improve and simplify the details of construction 25 of drop extensions for chandeliers.

In the drawings, Figure 1 is a sectional elevation on the center line, showing my extension complete arranged for two lamps, but 30 showing one only of the two. Fig. 2 is a side elevation approximately full size, showing a modified form of stop for the spring-raising drum. Fig. 3 is a sectional side elevation on the center line approximately full size and to 35 double the scale of Fig. 1. Fig. 4 is a detail.

Referring now to the drawings, in which like numerals indicate the same or like parts in all the views, 1 is an oil-reservoir, supported on a tube 2, to which it is fastened at 40 the points 3, preferably by brazing, to form a perfectly-tight joint.

4 is one of the usual forms of cap to permit filling the reservoir. From this reservoir a feed-tube 5 of fixed length leads downward, 45 either circling around the tube 2, as indicated, or running straight down alongside the tube, either inside or out, as may be desired, and terminating at a T 6, more clearly shown in the detailed view Fig. 4, which T is made

50 with two tubes 7 leading out therefrom hori-

zontally to the vapor-lamps 8, one of which only is illustrated. This T can be made, if so desired, for three or more connections instead of the two (only) shown. 9 and 10 are the usual form of shut-off or needle valves, 55 one of which, 9, may be omitted, if so desired. Should it be wished, however, the valve 9 may be shut off and a bracket of any desired shape substituted for the vapor-burner 8, in which case an oil-lamp could be used 60 with the form of chandelier shown. In case it should be desired to use the chandelier for kerosene-lamps the oil-reservoir 1, the tube 5, and the valve shown can be omitted, thereby reducing the cost of construction. These points are 65 material only as showing that while my invention is primarily for a vapor-lamp, it may be used partially as a support for an oil-lamp or entirely for an oil-lamp or other form of light.

The T 6 is supported by a double frame 11 70 and 12, made integral with a screw-socket 13 at its lower end, into which the T 6 screws, and also formed with a screw-socket 14 at its upper end, into which socket the tube 2 screws. The reservoir 1, the tube 2, the frame 11 and 75 12, and feed-tubes 5 and 6 are thus made one integral piece and move up and down together, as will be more fully hereinafter explained.

The frame 11 12 supports a center shaft 15, preferably made of a short section of hollow 80 tubing, having one side open, as shown at 16, Figs. 2 and 3, to form a slot in which the inside end of the spring 20 fastens. This shaft is prevented from turning by a pin 17, resting against stops 18 and 19, formed on the 85 frame 11. The stop 18 is preferably placed on the center line, in which case the upper end of the pin 17 is bent to one side, forming a shoulder which prevents removal when the spring 20 is holding it against the said stop 90 18. Should it be desired to use a left-hand spring or, what is the same thing, to reverse the position of the spring 20 now in use, this stop 18 may be used equally as well, and the pin 17 will bear against it in the same manner 95 that it now does, though on the opposite side, and will be equally prevented from accidental removal.

20 is a spring which counterbalances the weight of the lamp, reservoir, and fixtures. 100

This spring is placed between sides 21 and 22, spaced apart by a short cylinder, which forms a drum on which a cord 24 is wound. The drum is completed by passing pivots 25 through from side to side.

- 26 is a ratchet-stop formed integral with the side 22 and having notches 27, which are adapted to be engaged by a stop 28 to prevent motion of the drum. This stop 28 is disengaged from the notches 27 by means of a rod 29, extending downward therefrom and connecting to a short arm 30, which extends inward until it comes centrally beneath the **T** 6, as will be noted especially by reference to Fig. 3. The **T** 6 is also made as a stop-valve, the stem of which 31 extends downward below the said **T** and is formed with a push-button 32, which serves the double purpose of a handle for operating the valve and for a knob 20 for raising and lowering the chandelier. The arm 30, above mentioned, extends inward below the center of the said **T** and is fastened to a shortsleeve 33, which surrounds the said valve-stem 31. This sleeve has a finger-pull 34, by 25 which it may be depressed when so desired. This finger-pull is placed in proximity to the knob 32, so that it may be grasped by the fingers of the hand when the knob 32 is resting in the palm of the hand. To disengage 30 the stop 28, it is therefore only necessary to shut the hand, and thereby depress the finger-pull 34 and with it the rod 29. The stop 28 is normally held in place by a spring 35, which bears against its under side and rests on a 35 screw-plug 36, screwed into the said frame 11. This plug is purposely longer than the socket into which it screws, so that it may be used to regulate the tenison of the spring 37. Formed integral with the frame 11 is a guide 40 for the said stop 28 and the spring 35. The lower portion is preferably closed while the upper part is slotted to guide the lug 38, formed on the stop 28 and to limit the motion of same.
- 45 From the drum 23 a cord 24 extends upward, passing over the roller 39 or the roller 40, which are pivoted in the frames 11 and 12, to the top of the fixture, at which point it is fastened to the supporting loop or hook 41. 50 For convenience the cord 24 may be stopped just after passing over the roller 39 and a rod 42 be used to replace a portion of it, though this is not material in construction. The lower part of the supporting-loop is threaded, 55 and the inner tube 43 is screwed into the same. This tube extends downward within the outer tube 2 and forms a guide on which the said tube 2 slides. It may be made to exactly fit the interior of the said tube 2, but is 60 preferably made smaller in diameter with projecting lugs 44 extending outward to fit the interior of the tube 2. At the upper end of the tube 2 is an annular projection 45, which extends inward and embraces the exterior 65 surface of the tube 43. When the lamp is

lowered, this projection comes against the upper projection 44 and serves as a positive stop against too much downward movement.

In Fig. 2 I have illustrated a modified form of the stop 28, which form consists of a lever 70 46, having a lug 47 to engage the notches 27, a tension-spring 48 to hold it in place, and arms 49 and 50 extending outward from the side frame 11 to support the pivot of the arm 46 and to support the end of the spring 48. 75 A rod 51 extends from the arm 48 downward to arm 30, which is similar to or identical with the arm 30 above mentioned.

The drum 23 and the mechanism connected therewith may be surrounded, if so desired, 80 by an ornamental casing 52.

53 is a knob on the shaft 15 to enable it to be readily turned to change the tension of the spring 20.

In use the entire fixture is suspended from 85 a hook or other support attached to the ceiling, which support engages the loop 41. To lower the lamp, the knob 32 is grasped and the fingers of the hand closed over the finger-pull 34, disengaging the stop 28 from the 90 notches 27, when the lamp may be pulled downward, the cord 24 unwinding from the drum 23 and winding up the spring 20. When the desired point is reached, the arm 34 is released and the stop 28 allowed to engage the 95 notches 27, firmly holding the lamp in position whether the reservoir is full or empty. The lamp may then be lighted or, if desired, may be filled and again raised to place by releasing the stop 28 and pushing it upward 100 slightly to admit the spring 20. When in place or in any position either raised or lowered, the oil or gasoline flows through the feed-tube 5 and the **T** 6 to the lamp-supply tube 7. If it is desired, the oil-supply may be cut 105 off at the **T** 6, in which case all the lights in the fixture are shut off or more of the valves 9 and 10 may be closed, and thereby one only of the lights be cut off.

It will be especially noted that the cord 24 110 being smooth and continuous and the entire fixture guided on a smooth tube that there is absolutely no jar on raising or lowering the lights, such as would be detrimental to the mantle of a vapor-lamp.

115 It is of course distinctly understood that while I have described the preferred form of my invention there are many details which may be varied without departing from the spirit of same. I therefore do not intend by 120 illustrating a single specific form to confine myself entirely to the details shown.

Having fully described my invention, what I claim, and desire to secure by Letters Patent of the United States, is—

- 125 1. In a vapor-lamp, the combination with a reservoir, a sliding tube integral therewith depending from said reservoir, side frames supported by said tube, a spring-drum journaled in said frames, a **T** supported by said 130

frames vapor-burners supported by said **T**, and an independent feed-tube leading from said reservoir to said **T**, of a supporting-loop, a guide-tube within said reservoir-tube, depending from said loop, and a flexible connector within said guide-tube and fastened to said spring-drum and to said loop, substantially as shown and described.

2. In a drop extension for vapor-lamps, the combination with a reservoir, a sliding tube integral therewith depending from said reservoir, side frames supported by said tubes, a sliding drum mounted in said frames, a **T** supported by said frames, burners supported by said **T** and an independent feed-tube from said reservoir to said **T**, of a supporting-loop a guide-tube within said reservoir-tube, depending from said loop, and a flexible connector within said guide-tube and fastened to said spring-drum and to said loop, substantially as shown and described.

3. In a drop extension for vapor-lamps, the combination with a supporting-loop, a guide-tube extending downward from said loop, a tube slidably mounted on said guide-tube, a storage-reservoir mounted on the upper end of said sliding tube, a frame fastened to the lower end of said sliding tube, rollers mounted in said frame, a spring-actuated drum mounted in said frame, a flexible connector from said drum to said loop, a stop for said drum, a **T** forming the lower end of said frame, tubes extending outward from said **T** and suitable vapor-burners supported by said tubes of an independent feed-tube from said reservoir to said **T**, substantially as shown and described.

4. In a drop extension for lamps, a suitable frame, a spring-drum mounted in said frame, a combined **T** and valve integral with the lower part of said frame, a valve-stem extending downward from said valve, a knob on the end of said valve-stem, a sleeve slidably mounted on said valve-stem, a finger-grip on the lower end of said sleeve, and an arm extending outward from said sleeve, of a notched wheel integral with said drum, a stop engaging the notches of said wheel, a spring holding said stop in engagement with said notches, and a rod extending downward from said stop, substantially as shown and described.

5. In a drop extension the combination with a guide-tube a suitable support therefor, a sliding tube mounted on said guide-tube, an oil-reservoir attached to the upper end of said sliding tube, an independent feed-tube leading downward from said reservoir, a frame integral with the lower end of said sliding tube, rollers mounted in the upper end of said frame, and a spring-drum mounted in said frame, of a **T** and valve supported by the lower end of said frame, a valve-stem extending downward from said valve, a knob on the end of said stem, a sleeve mounted on said valve-stem, and an arm extending outward from said sleeve, all substantially as shown and described.

6. In a vapor-lamp the combination with a reservoir, a tube depending from said reservoir and supporting a frame, and a spring-balance drum mounted in said frame, of a **T**, tubes extending outward from said **T** and carrying suitable burners, a feed-tube leading into said **T** and a cut-off valve in said **T**, substantially as shown and described.

7. In a vapor-lamp the combination with a reservoir, a tube depending from said reservoir and supporting a frame, and a spring-balance drum mounted in said frame, of a **T**, tubes extending outward from said **T** and carrying suitable burners, a feed-tube leading from said reservoir to said **T**, a valve-seat in said **T** adjacent to the entrance of said feed-tube and a valve having a stem extending below said **T**, substantially as and for the purposes set forth.

8. The combination with a spring-actuated drum, a shaft for said drum and a frame carrying said shaft of a lug extending from said frame, holes in said shaft, a pin through said holes having one end bent to one side to form a shoulder and offset to come under and against one side of said lug, substantially as shown and described.

In testimony whereof I have signed my name to this specification in the presence of two subscribing witnesses.

VINCENT A. MENUEZ.
